(57) **CLAIM**

The ornamental design for a solar cell array, as shown and described.

DESCRIPTION

FIG. 1 is a top plan view of a solar cell array; and, FIG. 2 is top plan view thereof shown in environmental use. The broken lines shown represent unclaimed subject matter only. Where the long-dash/short-dash broken lines abut the claimed matter it is understood that those broken lines represent an unclaimed boundary between claimed and unclaimed surfaces. None of the broken lines form any part of the claimed design.
